UNITED STATES PATENT OFFICE.

ALLAN K. PRUDEN, OF ST. PAUL, MINNESOTA, ASSIGNEE TO THE METAL SHELTER COMPANY, OF ST. PAUL, MINNESOTA, A CORPORATION OF MINNESOTA.

SHEET-METAL CONSTRUCTION.

1,008,491.

Specification of Letters Patent. Patented Nov. 14, 1911.

Application filed January 12, 1910. Serial No. 537,723.

To all whom it may concern:

Be it known that I, ALLAN K. PRUDEN, a citizen of the United States, residing at St. Paul, in the county of Ramsey and State of Minnesota, have invented certain new and useful Improvements in Sheet-Metal Construction, of which the following is a specification.

My invention relates to improvements in sheet metal construction, its object being particularly to provide an improved method of joining together and supporting the different sections composing a portable building.

To this end my invention consists in the features of construction, combination and arrangement of parts hereinafter particularly described and claimed.

In the accompanying drawings forming part of this specification, Figure 1 is a perspective view of a building embodying my features of invention broken away; Fig. 2 is a top view of a portion of a wall shown partly in cross section; and Fig. 3 is a perspective view of one corner of the roof.

In the accompanying drawings A represents a wall section. Each section or plate has its side edges curled, the opposite edges being curled oppositely, and the meeting edges of adjacent plates being interlocked by carrying the curl of one plate around the curl of the next. Rods 2 are passed through the openings formed by said curls and suitably secured as by nuts 3 at their lower ends to a sill 5. The eave beam 4 carries a downwardly extended flange 6 formed preferably with a channel 7 in its lower end to receive the corresponding edges of the roof plates 8. The eave beams are carried upwardly at the ends of the building and suitably connected with the ridge member, the channel 7 thus extending entirely around the building. The upper ends of the roof plates extend into the channel 9 of a ridge member 10. The eave beams upon opposite sides of the building are connected by rods 11. The roof sections or plates are constructed and joined together in a manner corresponding to the wall sections A. As will be evident the portion of the ridge member constituting the top wall of the channel 9 will cover the upper ends of the roof plates constituting a water shed. As shown, the eave beam is formed with downward parallel flanges

forming an intermediate channel into which the upper ends of the wall sections project, the lower ends of the wall sections bearing against the vertical flange of the angle iron sill beam 5. The structure is adapted to be supported by downwardly extending posts 13 suitably secured underneat the sill.

As shown I preferably fit a packing 14 of rubber or other suitable material within the channel 9 in the ridge member, filling the space between the upper end of said channel and the roof sections, and constituting a tight joint.

I claim as my invention:

1. In a construction of the class described, wall sections comprising a plurality of plates having interlocking curled edges, the free edges of the curl along one side of the plate being interspaced from the plate a distance greater than the diameter of the adjacent curl in the next plate whereby to allow the larger curl to be laterally slipped over the smaller curl, a roof carrying member supported upon the upper ends of said face, and rods positioned within the interlocking curls of said plates.

2. In a construction of the class described, a roof carrying member formed with a channel upon its underside, a side wall removably fitted within said channel comprising a plurality of plates having interlocking curled edges and rods passing through said curled edges, the free edge of the curl upon one side of the plate being interspaced from the plate a distance greater than the diameter of the curl and contained rod upon the adjacent edge of the next plate whereby to allow said first mentioned curl to be laterally slipped over said last mentioned curl and rod.

3. In a construction of the class described, a ridge member, an eave member, said ridge and eave member being formed with corresponding channels, a roof removably fitted in said channels, a filling within one of said channels and between the inner wall of the roof and a wall fitted in connection with said eave member.

4. In a construction of the class described, a wall, an eave supported above the same and formed with a downwardly extending flange, a ridge member formed with a channel, and a roof removably supported at its

lower end upon said eave flange and extending at its upper end into the channel of said ridge.

5. In a construction of the class described, a ridge formed of a single piece of sheet metal bent to form channels upon its opposite sides, a coöperating eave member, roof plates fitting at their upper ends in said channels and at their lower ends supported

by said eave members, and wall plates supported underneath said eave members.

In testimony whereof I affix my signature in presence of two witnesses.

ALLAN K. PRUDEN.
